TURBO-TEARDOWN SWIVEL FIXTURE

Claude M. Harper, Westlake Village, Calif., assignor to
Roto-Master, Inc., North Hollywood, Calif.

Filed Jan. 26, 1973, Ser. No. 327,605

Term of patent 14 years

Int. Cl. D15—99

U.S. Cl. D54—13 A

Fig. 1.

Fig. 2.

Fig. 3.

Fig. 4.

Fig. 5.

Fig. 6.

Fig. 7.

FIG. 1 is a perspective view showing my new design of a turbo-teardown swivel fixture, depicting the body of a turbo charger in phantom lines;

FIG. 2 is a top view of my turbo-teardown swivel fixture;

FIG. 3 is a view taken along the line 3-3 of FIG. 2;
 FIG. 4 is a view taken along the line 4-4 of FIG. 3;
 FIG. 5 is a view taken along the line 5-5 of FIG. 4;
 FIG. 6 is a view taken along the line 6-6 of FIG. 5;
 and

FIG. 7 is a view taken along the line 7-7 of FIG. 6.
 I claim:

The ornamental design for turbo-teardown swivel fixture, as shown.
